SLIDING DOOR HANGER

Clarence B. Riser, Sterling, Ill., assignor to Lawrence Brothers, Inc., Sterling, Ill., a corporation of Illinois

Filed Feb. 4, 1958, Ser. No. 713,133

3 Claims. (Cl. 16—105)

The present invention relates to a novel door hanger structure, and more particularly to adjustable hanger structure of the type suitable for mounting sliding doors.

One object of the invention is to provide a translatable door hanger which provides for support and vertical adjustment of a sliding door by means of an improved and highly simplified construction which can be confined within a vertically and horizontally compact space located above a sliding door and contained substantially within the normal thickness of a sliding door while at the same time being readily accessible for adjustment by a tool extending upwardly closely alongside a door supported by the hanger.

Another object of the present invention is to provide a novel hanger structure for doors and the like of the above described type which structure may be readily and economically produced and easily assembled with a door.

Other objects and advantages of the present invention will become apparent from the following description and the accompanying drawings wherein:

Fig. 1 is a fragmentary elevational view showing a sliding door installation utilizing hanger structures incorporating features of the present invention;

Fig. 2 is an enlarged fragmentary cross sectional view taken along line 2—2 in Fig. 1;

Fig. 3 is a fragmentary sectional view taken generally along line 3—3 in Fig. 2;

Fig. 4 is a sectional view taken generally along line 4—4 in Fig. 2; and

Fig. 5 is an exploded perspective showing a hanger structure incorporating features of the present invention.

Referring now more specifically to the drawings wherein like parts are designated by the same numerals throughout the various figures, an installation is shown in Fig. 1 wherein a sliding door 10 is supported from an overhead track 12 by means of a pair of hanger structures 14 which are made in accordance with the present invention. As will be understood, the door 10 is adapted to be moved to and from the closed position shown in Fig. 1 and an open position within a door receiving pocket 16 formed in the wall structure 18 in a known manner. As indicated best in Figs. 2 and 3 the track 12 disposed within and secured to a suitable header member 20.

The hanger structure 14 comprises a carriage assembly 22 and a bracket assembly 24 which are adjustably interconnected with each other in the manner described fully below. The carriage assembly comprises an elongated generally vertically disposed plate-like body member 26 having rollers 28 and 30 mounted adjacent its opposite ends by means of stub shafts 32 and 34 respectively. As will be understood, these rollers are adapted to ride on an upwardly facing surface of the track member 12. A finger element 36 is welded or otherwise secured to the body member 26 for extending beneath the track member, which finger element terminates in an upwardly inclined portion 38 having a threaded aperture which

2

receives a screw 40. The screw 40 may be selectively adjusted to the position shown best in Fig. 2 so as to prevent the carriage assembly from being raised sufficiently to disengage the rollers from the track member 5 and to a retracted position which will permit the carriage assembly to be applied or removed from the track member. Another finger element or lug 42 is provided, which finger element 42 extends oppositely from the finger element 36 and in the embodiment shown is integral with the body member 26. This finger element is provided with an upwardly inclined end portion 44 which has an aperture therethrough for the purpose described below.

The bracket assembly 24 comprises a bracket member 46 having an upstanding portion 48 and a laterally extending portion 50. A plurality of apertures 52 is provided in the bracket portion 50 so that the bracket is adapted to be secured to the upper margin of a door or the like by means of a plurality of screws 54. A finger element or lug 56 is struck from an intermediate section of the upstanding bracket portion 48 and extends laterally therefrom and oppositely from the bracket portion 50. The finger portion 56 is provided with an outer upwardly inclined end section 58. The end section 58 is inclined in substantially the same manner as the end section 44 of the finger element 42.

In accordance with a feature of the present invention, the carriage and bracket assemblies are adjustably interconnected by means including a screw member 60 having an enlarged head 62 underlying the finger portion 58 and a threaded shank which extends upwardly through aligned apertures in the finger portion 58 and the finger portion 44. A nut element 64 overlies the finger portion 44 and threadedly receives the screw shank. As shown best in Figs. 2 and 5, the nut element 64 and the finger portion 44 are provided with complementary rounded surfaces restraining the nut member against rotation. A spring 66 is mounted on the screw shank and compressed between the finger portions 44 and 58 so as normally to maintain the nut member in engagement with the finger portion 44. It will be noted that the finger portions 44 and 58 are inclined so that the screw member is arranged in a manner which displaces the slotted head thereof from the upper edge of the door and which exposes the slotted head so that it may be readily engaged by means of a screw driver 68 or the like indicated in broken lines in Fig. 2. In other words, the structure is such that the longitudinal axis of the screw member is aligned with the gap between the upper edge of the door and the adjacent wall of the jamb member 20. With this structure it will be appreciated that the door may be readily either vertically raised or lowered merely by turning the screw member 60 in the appropriate direction.

The carriage and bracket assemblies are provided with cooperable guide means which retain them against lateral separation from each other and against relative tilting movement so that undue lateral or bending stresses are not imposed upon the screw member. More specifically, the carriage body member 26 is provided with a pair of vertically elongated slots 68 and 70 through which pins 72 and 74 extend. These pins have reduced diameter end portions 76 and 78 which extend through suitable apertures in the upstanding portion 48 of the bracket and which end portions are upset so as to secure the pins to the bracket. The free ends of the pins are provided with enlarged heads 80 and 82 which overlie the body member 26 for preventing lateral separation of the body member from the upstanding bracket portion. It will be noted that the body member 26 is provided with a central slot 84. This slot is adapted to accommodate the upper end of the screw member 60

especially when the screw is adjusted so as to raise the bracket with respect to the carriage assembly.

While the preferred embodiment of the present invention has been shown and described herein, it is obvious that many structural details may be changed without departing from the spirit and scope of the appended claims.

The invention is claimed as follows:

1. A sliding door hanger comprising, in combination, a narrow downwardly open horizontal channel, a horizontal support track supported on said channel and extending into the central portion thereof, a generally flat substantially vertical carriage frame member disposed in vertically overlapping relation to one side of said track, carriage wheels journaled on said frame member and supported on said track, a hold-down member on said frame member extending horizontally therefrom in closely underlying relation to said track, an adjustable stop member mounted in said hold-down member in opposing relation to said track for engagement with the latter to prevent dislodgement of said wheels from the track, a door support bracket including a generally flat vertical portion slidably overlapping said frame member and including a horizontal flange portion underlying said track and adapted to fit against the upper edge of a door, guide means on said frame member coacting with said vertical bracket portion to guide the latter for vertical movement with respect to said frame member, a first support lug on said frame member projecting laterally from the side thereof opposite from said track and defining a first aperture therein spaced horizontally from said frame member, a second support lug joined to said bracket adjacent the juncture of said vertical and flange portions thereof and projecting laterally away from said flange in underlying relation to said first lug and defining a second aperture located horizontally outwardly from said first aperture, a threaded nut member overlying said first lug, a threaded adjustment element extending upwardly through said second aperture and said first aperture respectively in a position inclined downwardly away from bracket flange portion, and said threaded element coacting with said nut member to effect a vertical displacement of said bracket relative to said frame member upon rotation of the threaded element.

2. A sliding door hanger adapted to be mounted in a vertically and horizontally compact downwardly open groove with the downwardly open end of the groove substantially flush with the top of a door to be supported from the hanger and with the edges of the groove spaced only slightly laterally therefrom; and comprising, in combination, a horizontal support track, an upright carriage frame member disposed in vertically overlapping relation to one side of said track, carriage wheels journaled on said frame member and support on said track, a door support bracket including a vertical portion slidably overlapping said frame member and including a horizontal flange portion underlying said track and adapted to

fit against the upper edge of a door, guide means on said frame member coacting with said vertical bracket portion to guide the latter for vertical movement with respect to said frame member, a first support lug on said frame member projecting laterally from the side thereof opposite from said track, a second support lug on said bracket projecting laterally therefrom in underlying relation to said first lug, said support lugs having aperture means therein with the aperture means in the second support lug offset horizontally outwardly from the aperture means in the first support lug, and threaded adjusting means interconnecting said lugs for adjusting the second lug and bracket vertically with respect to the carriage frame and received in said aperture means in inclined position with the lower accessible end of the threaded adjusting means below the second support lug and disposed laterally outwardly of the horizontal flange portion of the door support bracket whereby to locate the accessible end of the inclined threaded adjusting means in position for convenient engagement by an adjusting tool inserted through the lateral space remaining between the downwardly open end of the groove and the door.

3. A sliding door hanger comprising, in combination, a relatively narrow and shallow downwardly open horizontal channel, a horizontal support track supported substantially centrally within said channel, a substantially vertical carriage frame member disposed within said channel and in overlying relationship to one side of the track, carriage wheels journaled on the frame member and supported on said track, a door support bracket including a substantially vertical portion slidably overlying the frame member and further including a substantially horizontal portion underlying the track in proximity to the downwardly open end of the channel and adapted to be secured to the upper edge of a door, guide means between the frame member and the vertical portion of the bracket to guide the bracket in vertical movement with respect to the frame member, a first apertured support lug on the frame member projecting laterally from the side thereof remote from the track, a second apertured support lug projecting from the bracket laterally of the horizontal flange portion thereof and underlying the first lug with the apertures disposed along an inclined axis extending toward the space between the adjacent edge of the downwardly open end of the channel and the edge of the horizontal portion of the bracket, and a threaded adjusting member supported by said support lugs with its accessible end positioned for access in the space between the edge of the downwardly open end of the channel and the horizontal portion of the bracket.
